CLAIM

The ornamental design for a label printer, as shown and described.

DESCRIPTION

FIG. 1 is a front, right, and top perspective view of a label printer, showing my design.

FIG. 2 is a rear, left, and bottom perspective view thereof.

FIG. 3 is a front, left, and bottom perspective view thereof.

FIG. 4 is a front elevation view thereof.

FIG. 5 is a rear elevation view thereof.

FIG. 6 is a left side elevation view thereof.

FIG. 7 is a right side elevation view thereof.

FIG. 8 is a top plan view thereof.

FIG. 9 is a bottom plan view thereof; and,

FIG. 10 is a partial enlarged view of an area labeled 10 in FIG. 1.

The evenly spaced broken lines depict portions of the label printer that form no part of the claimed design. The dot-dash broken lines indicating an enlargement portion of the design forms no part of the claimed design.
